FIG. 1.

FIG. 2.

Inventor:

Alfred E. Ischinger.

Attorney.

UNITED STATES PATENT OFFICE

164,756

STOCKING

Alfred E. Ischinger, Reading, Pa.

Application July 20, 1951, Serial No. 15,967

Term of patent 14 years

(Cl. D47—7)

To all whom it may concern:

Be it known that I, Alfred E. Ischinger, a citizen of the United States of America, residing at 410 Kenhorst Boulevard, Reading, in the county of Berks and State of Pennsylvania, have invented a new, original, and ornamental Design for a Stocking, of which the following is a specification, reference being had to the accompanying drawing, forming part thereof.

Figure 1 is a front perspective view of a stocking embodying my novel design, the rear of the stocking having the usual appearance of a standard or conventional stocking of modern construction and design.

Figure 2 is an enlarged fragmentary front elevational view of the stocking part indicated by the dot and dash outline in Figure 1, and shows the ornamental line approximately to full scale dimensions and in relation to an actual stocking.

The design comprises a longitudinally extending line located at the front of the stocking which extends from the welt area to the ankle area and

there ends in an ornamentation, said line and ornamentation being of a contrasting appearance in relation to the adjacent stocking material.

I claim:

The ornamental design for a stocking, as shown and described.

ALFRED E. ISCHINGER.
